US00D446183S

(12) United States Design Patent **(10) Patent No.:** **US D446,183 S**
Miyashita **(45) Date of Patent:** **** Aug. 7, 2001**

(54) RECHARGEABLE BATTERY

(75) Inventor: **Shin Miyashita, Tokyo (JP)**

(73) Assignee: **Sony Corporation, Tokyo (JP)**

(**) Term: **14 Years**

(21) Appl. No.: **29/121,482**

(22) Filed: **Apr. 7, 2000**

Related U.S. Application Data

(62) Division of application No. 29/099,985, filed on Feb. 1, 1999.

(51) LOC (7) Cl. **13-02**

(52) U.S. Cl. **D13/103**

(58) Field of Search D13/103; 429/96-100, 429/156, 163, 174

(57) CLAIM

The ornamental design for a rechargeable battery, shown and described.

DESCRIPTION

FIG. 1 is a perspective view of a first embodiment of a rechargeable battery showing my new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof; and

FIG. 7 is a bottom plan view thereof.

FIG. 8 is a perspective view of a second embodiment of a rechargeable battery showing my new design.

FIG. 9 is a top plan view thereof;

FIG. 10 is a left side elevational view thereof;

FIG. 11 is a front elevational view thereof;

FIG. 12 is a right side elevational view thereof;

FIG. 13 is a rear elevational view thereof; and,

FIG. 14 is a bottom plan view thereof.

FIG. 15 is a perspective view of a third embodiment of a rechargeable battery showing my new design;

FIG. 16 is a top plan view thereof;

FIG. 17 is a left side elevational view thereof;

FIG. 18 is a front elevational view thereof;

FIG. 19 is a right side elevational view thereof;

FIG. 20 is a rear elevational view thereof; and,

FIG. 21 is a bottom plan view thereof.

FIG. 22 is a perspective view of a fourth embodiment of a rechargeable battery showing my new design;

FIG. 23 is a top plan view thereof;

FIG. 24 is a left side elevational view thereof;

FIG. 25 is a front elevational view thereof;

FIG. 26 is a right side elevational view thereof;

FIG. 27 is a rear elevational view thereof; and,

FIG. 28 is a bottom plan view thereof.
